UNITED STATES PATENT OFFICE.

ERNEST WELLS CRUIKSHANK, OF BALTIMORE, MARYLAND.

RECORD-LEAF.

SPECIFICATION forming part of Letters Patent No. 759,679, dated May 10, 1904.

Application filed February 1, 1904. Serial No. 191,573. (No model.)

To all whom it may concern:

Be it known that I, ERNEST WELLS CRUIKSHANK, a citizen of the United States, residing at Baltimore, in the State of Maryland, have 5 invented a new and useful Record-Leaf, of which the following is a specification.

This invention relates to a record-leaf combined with communication-blanks; and the principal object of the invention is to provide, 10 in combination with a plurality of invoice-forms, letter-heads, note-heads, or the like, a record-leaf so arranged relatively to the invoice-forms or letter-heads that carbon copies may be made directly upon both sides of the 15 record-leaf when the invoice-forms or letter-heads are used and the record-leaf bearing the carbon transcripts on both sides be then separated from the invoice-forms or letter-heads and filed in a suitable binder as a day-book or journal leaf.

As is well known, the ordinary procedure in recording the shipments of goods is to make out the invoice in copying-ink, to take a letter-press copy from the invoice after it is 25 filled out, and then copy from the letter-press copy of the invoice into the day-book or journal. This mode of procedure is tedious and is also objectionable, because the letter-press copies made from the invoice are often so 30 indistinct that it is extremely difficult if not impossible to make entries therefrom into the day-book or journal without error. It is therefore extremely desirable to provide some means whereby at the time the invoice is 35 made a duplicate thereof may be made upon the leaf of the day-book or journal. The device forming the present invention, and hereinafter fully described and claimed, forms means whereby the desired record may be obtained when the invoices or letters are written 40 out, and when the invoices or letters are detached from the record-sheet it will be ready for filing in a binder. The posting of the accounts to a ledger may then be made directly 45 from the record-sheet in the day-book or journal, and no copying from a letter-press copy of the original invoice or letter is necessary.

In describing the invention reference is had to the accompanying drawings, in which I 50 have illustrated an embodiment of the inven-

tion in which the record-sheet is combined with invoice-forms; but it is obvious that the ruling of the invoice-forms and the record-sheet may be varied without departing from the invention and that the device may so be 55 adapted for use in recording letters instead of invoices.

In the drawings, Figure 1 is a front view of the record-leaf with the invoice-forms attached thereto. Fig. 2 is a rear view of the 60 record-leaf with the invoice-forms attached thereto. Fig. 3 is an end view of the record-leaf with the invoice-forms folded thereon in position to receive copying-sheets between 65 the forms and the record-leaf.

Referring to the drawings, A represents the record-leaf, preferably provided with openings B B near one margin to receive the securing members of a suitable binder and being numbered at the upper corner opposite 70 the binding-margin. As both sides of the record-leaf are to be made use of, one side is numbered 1 and the other side is numbered 2. At each side of the record-sheet and separated therefrom by a row of perforations C 75 there are arranged a plurality of invoice-forms D. The invoice-forms at the right side of the leaf are printed on the front surface and those upon the left side of the sheet are printed upon the rear surface, so that when 80 the combined structure is folded, as shown in Fig. 3, the record-leaf is interposed between the two sets of invoice-forms.

Each invoice-form is separated from the adjacent invoice-form by rows E of perforations 85 perpendicular to the rows C, and when the invoices are filled out they are detached by tearing along the lines of perforations in the usual manner.

In making out invoices and making records 90 thereof at the same time a carbon-sheet is placed between one set of forms and the record-sheet, and the invoice-forms of that set are then filled out with pen, pencil, or type-writer, as may be preferred. The invoices being filled 95 out, the sheet of carbon-paper is removed from between the forms and the record-leaf and the invoices are separated from the record-leaf by tearing along the lines C of perforations. The other set of invoice-forms will then be 100

- filled out in a similar manner, a sheet of carbon being interposed between the forms and the other side of the record-leaf. All the invoice-forms having been filled out and detached from the record-leaf, duplicates of the invoices will be presented upon the two sides of the record-leaf and the leaf will then be ready for filing within the temporary binder in lieu of an ordinary day-book leaf.
- 5 When the record-leaf is combined with note-heads, bill-heads, or letter-heads, the mode of using the device is precisely similar, except that instead of invoices letters, bills, or other communications will be written.
- 10 While I have shown the invention as embodied in a device in which each record-leaf is associated with six invoice-forms, three upon each side of the leaf, it is obvious that the leaf may be made smaller or larger, as desired, and the number of forms associated therewith varied to suit the circumstances of any particular case. Thus it may be desir-

able to provide only one invoice-form on each side of the record-leaf, or, on the other hand, it may be desirable to provide half a dozen ²⁵ forms on each side of the leaf.

Having thus described the nature and use of my invention, what I claim as new, and desire to secure by Letters Patent, is—

A record-leaf similarly ruled upon the reverse and obverse and having attached thereto at opposite sides a plurality of sheets separated from the record-leaf by weakened lines, one of said sheets being provided upon the obverse with printed matter and the other ³⁰ ³⁵ sheet being provided upon the reverse with printed matter.

In testimony that I claim the foregoing as my own I have hereto affixed my signature in the presence of two witnesses.

ERNEST WELLS CRUIKSHANK.
